UNITED STATES PATENT OFFICE.

ALBERT H. MERRILL, OF FLORENCE, CALIFORNIA.

TABULAR REFERENCE DEVICE.

SPECIFICATION forming part of Letters Patent No. 762,546, dated June 14, 1904.

Application filed February 17, 1902. Serial No. 94,544. (No model.)

To all whom it may concern:

Be it known that I, ALBERT H. MERRILL, a citizen of the United States, residing at Florence, in the county of Los Angeles and State 5 of California, have invented a new and useful Tabular Reference Device, of which the following is a specification.

This invention may be applied to various display devices, and among others relates to that class of calculators in which a table showing results calculated from certain data is so arranged on relatively moving parts that by properly manipulating the same any desired result within the capacity of the device may 15 be exposed to view at a sight opening or openings.

An object of this invention is to provide in a small compass, as in a series of cards arranged in pack form, a table or tables of great 20 extent which the user can instantly and conveniently adjust to exhibit the result which he desires to determine. By reason of the cards being held in pack form the device may be of a size that can readily be carried in the 25 pocket and yet embrace a table of calculations equal to that contained by a much larger device otherwise constructed, or a table so large as to heretofore require figures too small to be easily read when contained in a pocket device 30 may be contained in an equal compass by my device and yet be printed in larger and easily-read type. I attain this desirable end by providing means for singly extending intermediate cards of the pack in combination 35 with devices for holding against frictional displacement the card or cards contacting with the one operated.

By this invention it becomes possible to provide within the compass of a convenient desk-ruler or a case which can be carried in the 40 pocket tables of multiplication and division involving several digits in the result. The invention may be embodied in different ways and for different purposes.

An object of this invention is to provide a device of this class which will be convenient, simple, compact, inexpensive, and accurate, being capable of supporting in convenient 45 position for instant and convenient examination a number of slides bearing tables of cal-

culations which may be quickly adjusted to enable persons to ascertain at a glance the total cost of any given quantity of merchandise at a determined price when the total money value and the price per unit of weight 55 or measure are known.

My invention is therefore adapted to be substituted for the more expensive computing devices now in use in the form of attachments to weighing-scales, being capable of embracing a larger table of numbers than is used with computing-scales and requiring less time for operation than is required to set a pair of computing-scales.

Although primarily intended for use in performing mathematical operations, the mechanism of my tabular reference device may also be used for an indexer, a mechanical directory, or for a list of words alphabetically arranged, such as might be found in a list of 60 words difficult to spell or in a small dictionary. It may also be used to display samples of paint, cloth, wall-paper, &c.

The invention embraces a tabular reference device comprising a plurality of superposed 75 sliding members having tabulated information thereon, a cover for said members, means for sliding any desired member a predetermined distance to bring the desired portion of said member into view, said means comprising means for operating and means for stopping such member. The means for operating and the means for stopping any member may be variously constructed without departing from the broad terms of this invention. Preferably the means for operating any member will comprise an arrangement of seats in the members, respectively, and a removable instrument to engage said seats, respectively, thereby to slide the members, and 80 an arrangement of stops on the cover to stop said instrument when it strikes the same. The several seats will be appropriately marked to indicate the character of the tabulated information which will be brought to view at the 85 appropriate place when the instrument is thus stopped, and preferably each of the sliding members will be furnished with a plurality of sight-openings, and the cover will also be furnished with sight-openings, the parts be- 90 95 100

ing constructed and arranged to normally provide a sight-opening or sight-openings entirely through the appliance, so that when any of the sliding members is moved from the normal position information carried thereon will be visible through the sight-opening or sight-openings from either side of the appliance.

- Each of the sliding members may have the same information arranged on its opposite sides; so that when certain information is exhibited to a person on one side of the appliance the same information will be visible from the other side, or, if desired, the appliance may be constructed with a portion of certain tabulated information on one side and an extension of like tabulated information on the other side, thus to embody an extensive table within a small appliance.
- Preferably the sliding members will have perforations through them to receive an instrument by which to be moved and will be so constructed and arranged that the perforations of all the sliding members will be open at both sides of the appliance when the parts are in normal position.

The accompanying drawings illustrate the invention in some of the forms in which I propose to embody the same.

- Figure I is a side view of a device embodying the invention in a form convenient for carrying in one's pocket. Parts of the cover of the box or casing are broken away to show parts underneath. Fig. II is a longitudinal section on line II II of Fig. I. Fig. III is a fragmental enlargement of a portion of Fig. II. Fig. III^a is a fragmental sectional detail illustrating the arrangement of the elastic cords and the plates, which are yieldingly held in normal position thereby. Fig. IV is an enlarged cross-section on line IV IV of Fig. I. Fig. V is an enlarged cross-section taken on line V V of Fig. I. Fig. VI is a side view illustrating the operation of the device. This view practically illustrates the reverse side of the device as shown in Fig. I, with the exception that a modification of the retracting mechanism and of the frame, box, or casing is shown. Fig. VII is a view of the edge of the device as shown in Fig. VI. Fig. VIII is a cross-section on line VIII VIII, Figs. VI and VII. Fig. IX is a view of a blank for a clip adapted to hold the frame together and also to provide means for readily attaching and detaching the elastic cords which retract certain parts inside the frame. Fig. X is a detail of a form of device for applying to the plates the pressure of the elastic cords. Portions of a cord are shown. Fig. XI is a side view of a form of the device adapted to be used for both multiplication and division and also containing certain modifications, especially in the retracting mechanism. By the appliance shown in this view the quantity of a commodity may be determined when the total value and the price per pound are

known. Fig. XII is an enlarged fragmental longitudinal section on line XII XII, Figs. XI and XV. Fig. XII^a is a detail of a form of fastening for rods D and E. Fig. XIII is an enlarged fragmental sectional detail of the modified form of retracting mechanism on line XIII XIII of Fig. XII. Fig. XIV is an end view of the part shown in Fig. XIII looking right from left of Fig. XI. Fig. XV is a cross-section on line XV XV of Figs. XI and XII. Fig. XVI is a plan of a ruler provided with my invention. Fig. XVI^a shows in detail a feature of construction of Fig. XVI. Fig. XVII is an enlarged fragmental view of the same, the cover being omitted, parts being broken away to show interior construction. Fig. XVIII is a fragmental plan of one of the covers. Fig. XIX is a fragmental longitudinal section illustrating the retracting mechanism, being taken from line XIX XIX of Fig. XVII. Fig. XX is a fragmental longitudinal mid-section of Fig. XIX on irregular line XX XX. Figs. XXI and XXII are cross-sections taken, respectively, on lines XXI XXI and XXII XXII of Fig. XVII.

For convenience of description I will consider first the invention as illustrated in Figs. I to X, inclusive. The cover or frame may be composed of two side members C C', held apart by edge pieces A and A' and end pieces B B', the whole being fastened together by any suitable means, glue, solder, or some other suitable substance with and without clips, respectively, being used in the two forms under consideration. In Fig. VI four clips a' a² a³ a⁴ are shown attached to the corners of the frame to strengthen it. The said covers C and C' may be of pasteboard, celluloid, metal, or other suitable material and are preferably of the same size and shape, each containing a row of equidistant transverse slots or sight-openings c' c² c³ and also a larger and more nearly square combined sight and operating opening c⁴.

Between the covers C C' are slidingly mounted a plurality of superposed exhibit members, preferably in the form of plates f' f² f³ f⁴. These plates are each provided with a plurality of sight-openings c' c² c³, preferably of the same size and shape as the corresponding openings in the covers. When the parts are in normal position, the openings in the sliding plates all coincide with each other and with the corresponding openings in the covers, so that normally the openings extend entirely through the device at the sight-openings of the covers. Each of the sliding plates is desirably furnished at one end with a perforated actuating-arm, as shown at g' g² g³ g⁴. Said arms are preferably integral with the body portions of their respective sliding plates and are provided with means for moving them, as seats or shoulders, preferably formed as rows h' h² h³ h⁴ of perforations. The outer arms g and g⁴ may be broader than the other

arms, if desired, to add to the strength of the device. This will be understood by reference to Fig. I, where the characters 4^f and 5^f designate the end corners of the arm g, and the characters 27^f and 28^f designate the like corners of the arm g^t, while 14^f and 15^f designate the like corners of the arm g'. 5

I have made provision whereby any one of the sliding plates may be actuated without moving any of the other sliding plates. For this purpose two retracting devices are employed to normally hold the sliding plates in their retracted position. One of these retracting devices is arranged to act upon the alternate sliding plates without interfering with the other sliding plates and the other retracting device is arranged to actuate the other sliding plates without interfering with the sliding plates actuated by the first-mentioned 15 retracting device.

Various forms of resilient retracting devices may be employed. In the forms shown in Figs. I and VI elastic cords are used for retracting the sliding plates. The alternate 20 sliding plates are respectively provided with a notch k, and the other sliding plates are provided with a notch k'. j and j' designate elastic cords which extend across the forward ends of the sliding plates and are caught in 25 the notches k k', respectively, of such plates, so that when any plate is drawn to the right in Figs. I to VI the cord which is in the notch of that plate will be extended, so that when the plate is again released the cord will 30 retract it. The plates are constructed and arranged to respectively engage only one of the cords, each cord leaving free the plates engaged by the other cord. The purpose of arranging the cords to operate the alternate 35 plates, respectively, is to assemble the sliding plates as close together as possible without causing the operation of one to actuate the others by friction thereupon.

Where a clip for the elastic cord is employed as hereinafter described, the cord will 40 be applied in two sections, the ends of which are connected with the clip and the frame of the device, respectively.

In the particular construction illustrated by 45 Figs. VI to VIII, inclusive, the covers C C', respectively, have two longitudinal slots i i', each slot being opposite the corresponding one in the other cover. Two endless elastic cords j j' are arranged to pull against the sliding 50 plates at the notches k k' in the ends of the said plates. These notches do not show in Fig. VI, but occupy the same position as in Fig. I, where they are clearly shown. The clips a and a' are preferably formed as metal plates, as 55 shown in Figs. VI, VII, and IX, being furnished with hooked portions z z', upon which the extremities of the cords j j' are looped, as shown in Figs. VI and VII. This arrangement makes it possible to easily remove a cord as 60 soon as it has been broken or weakened by use

and to put on a new one. The end pieces B B' are preferably formed with raised portions or beads b on each side. In the end piece B each of these raised portions contains two notches b', as shown, so that when the device is laid upon a plain surface its weight does not bear upon the cords j j'. By this arrangement the cords are guarded against wear and their free movement during the operation of the device while lying on a plain surface is provided for. 70 75

In the form of my invention shown in Figs. I to V, inclusive, the cords j j' are placed inside the covers, being single instead of double at the point where they pass over the notches k k'. In this arrangement stronger cords should be 80 used, and they should be looped over the end piece B before the frame is put together. A notch j², Fig. I, may be cut on three sides of the end piece B at the points designated, so as to keep the cords j j' in place and sink them to 85 the level of the surface of the end piece. These elastic cords normally keep all of the plates in the retracted position, as shown in Fig. I.

If no reference is made to the notches k k', the outline of each of the five sliding plates, 90 (shown in Figs. I to VI,) including the arms by which they are to be operated, respectively, may be described as follows, each number indicating the position of an external corner. Referring to Fig. I, the corners of the plate f¹ 95 and its arm g lie at the points designated by 1^f 2^f 3^f 4^f 5^f 6^f 7^f 8^f 9^f 10^f. The external corners of f² and its arm g' lie at 1^f 11^f 12^f 3^f 13^f 14^f 15^f 16^f 17^f 10^f; of f³ and g³ at 1^f 2^f 18^f 19^f 20^f 21^f 7^f 8^f 9^f 10^f; of f⁴ and g⁴ at 1^f 11^f 12^f 3^f 22^f 23^f 24^f 25^f 100 17^f 10^f; of f⁴ and g⁴ at 1^f 2^f 26^f 27^f 28^f 8^f 9^f 10^f.

In Fig. VI, to avoid confusion, the corners are not all designated, the outermost forward corners 4^f and 28^f of plates f and f^t, respectively, and the corners 23^f and 24^f of the arm 105 g³ of plate f³, which is there shown out of normal position, being the only corners marked. From this description of the form of the plates it will be seen, referring to Figs. I and III^a, that the cord j normally holds the first or upper plate f and the third and fifth plates f² and f⁴ in the retracted position, and the cord j' in like manner retains the second and fourth plates f¹ and f³ in the retracted position. The 110 cut-away portions of the plates next to the notches k k' are thus so arranged that only one cord is extended at a time by the operation of a plate, the other cord retaining its normal position and holding against frictional displacement the plate or plates next to the one being 115 operated.

The slots in the covers of the case and in the plates are each preferably of a less width than the portion of the cover between the adjacent slots, and each plate is movable at variant distances, so that the desired indicators, as numbers, colors, or other desired matter on any plate, may be brought into view by moving the plate the proper distance. 120 125

The numbers d of the table are placed on 130

the plates in columns and longitudinal rows, the spaces d' of the columns corresponding with the distances between the centers of the perforations through the arms $g' g$, &c., seen 5 from each side of the appliance through one or the other of the large openings c' .

The opening c' is substantially as wide as the distance between the adjacent spaces, in order to permit of each column of numbers on 10 each of the plates being brought into register with the openings in the case. By constructing the parts in this manner the number of slots or openings in the case may be limited in number without decreasing the capacity of 15 the instrument, and at the same time greater accuracy is secured by locating the columns of numbers on the covers so far apart that they are not confusing.

In operating the device to consult the table 20 a pointed instrument may be used in the ordinary way. The numbers in the table on the body of the plates are so arranged with relation to the perforations in the rows $h' h$, &c., that when the point of a pencil p or other suitable instrument is inserted into a perforation 25 and its plate is thereby moved until the instrument strikes the stop formed by the edge c^5 of the aperture, as shown in Fig. VI, three numbers of each longitudinal row of the portion 30 of the table on the slide or plate will come into view, one being seen through each of the slots $c' c^2 c^3$, as is clearly shown in Fig. VI. On the outer sides of the covers, aligned with the longitudinal rows of numbers on the body 35 of the plates, are numbers in columns $r' r' r^2$, extending along one side of each of the slots $c' c^2 c^3$, respectively.

When the device is to be used for multiplication, the numbers in the table represent the 40 products obtained when the numbers on the covers are used for one set of factors and the numbers on the arms are used for the other set of factors. These three sets of numbers—viz., those on the body of the plates, those on 45 the arms, and those on the covers—are so arranged with relation to each other that the products of multiplications may be determined in the following manner, as is clearly illustrated by Figs. VI and VIII.

To multiply any number contained in the 50 set of numbers comprised in the columns $r' r^2$ by 32, for example, insert the point of the pencil or other instrument p into the perforation marked "32" and pull the plate f^3 to the 55 right until the instrument strikes against the edge of the opening c^4 , which constitutes the stops c^5 for all of the plates, when the plate f^3 will be in the position shown in Fig. VI. When the plate is in this position, the product 60 of one-fourth multiplied by thirty-two—viz., eight—will appear opposite " $\frac{1}{4}$," which is the top number in the column r ; "640," the product of thirty-two multiplied by twenty, will be exposed in line with the number "20," and 65 so on with all the numbers embraced by the

device. After a desired product has been ascertained the instrument p may be removed and one or the other of the elastic cords $j' j$ (the cord j in the present instance) will return 70 the plate to its normal position.

The operating-aperture c' on each side of the case exposes all of the operating-openings h in the normal position of the slide. Each operating-aperture constitutes a cut-away portion of the case opposite the aperture in the 75 other side to enable the operating means to penetrate the slide without obstruction by the case.

From the foregoing description the mode of operation will be plain, since it is uniform in 80 all cases. Attention need only be called to the fact that the numbers on the arms may run from " $\frac{1}{2}$ " or other chosen number to "25" or any other suitable number on one side and from the latter to "50" or some other 85 suitable number on the other side, omitting any numbers—such as "1," "5," or "10," for instance—which may be deemed desirable to omit. The numbers in the columns $r' r' r^2$ may or may not be the same on both sides of 90 the device. Since the operating instrument p may be inserted into the perforations from either side, the capacity of the device is double what it would be if it could be operated from one side only. 95

The perforations are desirably located along the mid-length of the arms $g' g$, &c., and said arms overlap each other nearly to the perforations, which construction is adapted to make them firm and strong as possible. If desired, 100 the perforations may be eyeleted, or thin metal strips may be attached to the arms having perforations coinciding with those in the arms.

r^3 designates index-numbers at the tops of 105 the several openings c', c^2, c^3 , and c^4 to indicate at a glance the limits of the factors pertaining to said openings, respectively.

In order to avoid obscuring by shadows the figures which are close to the edges of the 110 openings c', c^2, c^3 and also in order to make allowance for any inaccuracy of adjustment of a plate when the same is brought into a reading position, said openings c', c^2, c^3 are somewhat wider than the columns of the figures to 115 be read therethrough.

The opening c^3 is preferably made a little shorter than the openings c' and c^2 , so as not to weaken the sliding plates too much where they are cut away opposite the ends of the 120 said opening c^3 .

The elastic cords $j' j$ tend to draw together the forward ends of the plates. In some cases this may cause friction enough to interfere with the proper retracting of the plates. To 125 avoid this, a rigid clip may be used, as illustrated in Fig. X. This clip may consist of a wire bent, as shown, at the points j^4 and furnished with hooks j^3 for the attachment of the elastic cords. 130

When thin plates are used, they may bow in the middle, and thereby interfere with each other, the edges at the openings c^1 c^2 c^3 of the plate moving, catching upon the edges at the corresponding openings in a plate above or below the same. To avoid this, small cords or wires s may be strung across the said openings. These cords s may be passed through holes s^1 s^2 near the ends of every alternate plate, the ends of each cord being connected together on the other side of the plate, so as to form a loop. If the cords are drawn tight enough to take up the slack, they will effectually remedy the difficulty referred to. This arrangement will also tend to separate the numbered faces of the plates from each other, thus preventing the characters from being worn off by friction.

When the slides are composed of cardboard or similar material, it may be desirable to employ some means to prevent fraying or roughening along the edges. This may be done by applying glue or some other suitable sizing.

In the device as shown in Fig. XI each of the sliding plates is intended to have the same table of numbers on its opposite sides, and the covers are also intended to be numbered alike, so that when a result is exhibited to a person on one side of the appliance the same information will be visible from the other side. Any convenient means (not shown) may be used to support the appliance in an edgewise position in order to more readily accomplish this purpose.

The appliance as shown in Fig. XI is adapted to be used for both multiplication and division, the space on the portion of the sliding plates to the left of the opening c^6 being occupied by a multiplication-table, while that to the right of this opening contains a table adapted to show the quantity of a commodity when the total value and the price per pound are known. d^2 indicates the pounds-columns. d^3 indicates the ounces-columns. These columns are so spaced that when a computation is made the pounds-column will aline with the heading "lbs." at the top of the opening c^7 , and the ounces-column will likewise fall under the heading "oz." The numbers in said columns are only approximate in some instances, nothing less than one-fourth ounces being noted in the form shown. r^6 designates a column of figures which indicate the money value of the amount purchased. The function now under consideration will be best understood by giving an illustration. To find what weight at one-half cent per pound can be purchased for any money value indicated in the column r^6 , insert the operating instrument p' into the perforation to the right of " $\frac{1}{2}$ " and move the same to the right until stopped by the stop c^{15} . This will bring the left-hand weight-indicating columns d^2 d^3 into view at the sight-opening c^7 . The number "10" will appear under the heading "lbs." and opposite the

number "5," thus indicating that five cents will purchase ten pounds at one-half cent per pound, and so on down the column. If the operating instrument had been inserted into the perforation to the right of "1 $\frac{1}{2}$ " "3" ⁷⁰ would have appeared opposite "5" under the heading "lbs." and "5" would be seen under the heading "oz.," thus indicating that five cents will purchase three pounds five and one-fourth ounces at one and one-half cents per ⁷⁵ pound.

The mode of operating the various embodiments of the invention is uniform. Consequently the manner of using the device shown in Fig. XI will be readily understood from ⁸⁰ the foregoing description.

When small characters are used in connection with a large number of plates, it may be difficult, owing to the depth of the hole through the upper plates through which the ⁸⁵ result must sometimes appear, to associate the appropriate number on the cover with the appropriate result-indicating number on a rearward plate. This difficulty may be overcome by separating the numbers on the plates into ⁹⁰ sections by means of horizontal lines d^5 and correspondingly dividing into sections the numbers in the indicating-columns r^3 r^4 r^5 r^6 by short horizontal lines r^7 . The lines d^5 and r^7 are alined with each other, as shown, and ⁹⁵ preferably separate the numbers in the columns into groups of five to facilitate locating the desired known quantities in reading the result.

Each number on the arms may be placed on ¹⁰⁰ the side of its perforation opposite its stop, so that such number (which always indicates one of the known quantities of a problem) may be seen next to the operating instrument when the slide is fully moved to show the ¹⁰⁵ desired result.

In Figs. X to XV, inclusive, means are shown for applying the retracting force simultaneously to each edge of the plate operated, thus to insure a more even action of the ¹¹⁰ plate. D and E indicate two hollow rods running lengthwise the frame near each side thereof. The said rods constitute means for supporting the retracting mechanism, which is the same on each side of the device and is ¹¹⁵ therefore, for convenience of description and illustration, described and fully shown only in connection with the rod E. Said rod E forms a guide for two external followers F' and an internal follower G. The said external ¹²⁰ followers F' may be respectively formed by fitting a collar F³, desirably rectangular in external outline, to one end of a sleeve F² and fastening it thereto by a screw F⁴ or F⁵. The screw F⁴ enters a screw-threaded hole through ¹²⁵ one side of the collar F³, passes on through a hole in the sleeve F², and projects into the rod E through a slot E' through the wall thereof. The follower F' is constructed the same as the follower F, excepting that the screw F⁵, which ¹³⁰

slides in the slot E^3 , does not project far enough into the rod E to interfere with the action of the spring H contained therein. Said spring H presses the follower G against the screw or pin F^4 , thereby retracting the follower F . The follower F is actuated by a spring I , mounted upon the periphery of the rod E . Every alternate sliding plate $f^5 f^7$, &c., is provided with two projections u and u' , upon which the collars of the external followers F bear in returning the plate to its normal position. The other plates $f^6 f^8$, &c., are furnished with projections $u^2 u^3$, whereby they are returned to normal position by the 15 pair of followers F' which are actuated by the external springs I , the followers F being actuated by the internal springs H . By this arrangement every plate is returned to the normal position by pressure applied to both 20 sides through the ears or projections.

In Figs. XI and XII, KK' indicate guiding-strips to keep the forward ends of the sliding plates in place. These guides are provided with lugs K^2 , which project through 25 corresponding holes in the covers to keep the said guiding-strips in place.

In Fig. XI another means is shown for avoiding the danger of the plates catching upon each other, hereinbefore referred to. Referring to the opening c^4 , the left edge thereof slants to the right at the ends, as shown at c^{10} and c^{11} , so that when the plate is operated it first closes the opening near the corners c^{12} and c^{13} and in thus passing in between the 35 plates above and below the bow thereof, if any, is at least partially removed before the central portion of the opening is closed up, so that there is less danger of a plate catching upon those next to it above or below. The 40 openings $c^4 c^5$, &c., are equally spaced apart, the space between said openings being desirably greater than the length of the extreme forward movement of the slides, so as to leave room for a margin m next to the left side of 45 each section of the table between the openings $c^4 c^5$, &c., so that in the extreme forward position of any plate during its operation no edge will appear through any of the openings $c^4 c^5$, &c. Hence no plate can at any 50 time catch at the beginning of the retracting movement. The covers may be composed of two metal plates or side pieces $A^2 A^3$, connected together along the four edges by the strips $B^5 B^6$, which are clenched to the said covers 55 by means of ears B^7 , being bent down into depressions A^4 and B^8 , formed in the side plates. The depressions A^4 in each cover serve not only for seats for the ears B^7 , but also for means to keep the sliding plates from 60 working in between the covers $A^2 A^3$ and the followers $F F'$ on either side. The covers $A^2 A^3$ are bent over and may be brought together at the ends. The guide-rods D and E have a segment cut away at each end. (Indicated by E .) When the parts are assembled,

the ends of the said rods are fitted into semi-circular openings A^6 through the end portions of the strips B^5 and B^6 , respectively, all longitudinal and rotary play being thus avoided.

Figs. XVI to XXII, inclusive, illustrate the invention as applied in a ruler. The body portion A^{10} of the ruler is chambered out, as shown by solid and dotted lines at N in Fig. XVI, the covers C^{10} and C^{11} being fastened to each side by any suitable means to inclose the chamber, thus to form a case or frame for the parts. The sliding plates $f^{20} f^{21}$, &c., shown in these views are of the same construction and arrangement as in Figs. I and VI except that they are more elongated and contain nine perforations in each arm instead of five. The retracting mechanism is applied to the sliding plates in a manner similar to that shown in Figs. I and VI, but consists of followers $F^{10} F^{11}$, slidably mounted upon 85 guide-rods $E^{10} E^{11}$ and retracted to normal position by springs $I^{10} I^{11}$. Said followers $F^{10} F^{11}$ may each be composed of two pieces, a U -shaped piece F^{12} embracing the guide-rod and connected by solder or other suitable means to a piece F^{13} , said piece F^{13} being provided with a shoulder or bent-out portion F^{14} , adapted to engage the shoulders $f^{30} f^{31}$ of the sliding plates. The sides of the chamber N may be grooved at n , being that portion opposite the opening c^4 . Said grooves n may be shaped to correspond with the convex portion of the U -shaped piece F^{12} , thereby providing means for preventing any rotary movement of the followers. Holes O may be formed as shown to provide sockets for the rods $E^{10} E^{11}$ and the springs $I^{10} I^{11}$, respectively, mounted thereon. The object of these sockets is to provide for the use of as long springs as possible.

In Figs. XVI, XVII, and XVIII, r^{17} and d^{15} , respectively, indicate lines on the cover and on the plates. These lines assist in locating and reading the result in the same manner as lines r^7 and d^5 described in connection with Fig. XI.

Plugs Q may be employed to hold in place the forward ends of the guide-rods $E^{10} E^{11}$. When the parts are assembled, the end of a rod is slipped into the socket q and the plug is fitted into the forward end of a hole O , being secured therein by glue or any other suitable means.

In multiplying nineteen and one-half by thirty-two use the perforation marked "32" and mentally add together the products of nineteen multiplied by thirty-two and one-half multiplied by thirty-two, both of which are shown at the same time. This method may likewise be employed in many other cases where one factor is a mixed number.

When the multiplicand contains more than two figures, proceed as follows: To multiply two thousand one hundred and forty-two by thirty-two, insert the operating instrument into the perforation marked "32" and note 130

the product of twenty-one (which comprises the first two figures of the multiplicand) times thirty-two and also of forty-two (the last two figures of the multiplicand) times thirty-two, both of which products appear at the same time. (See Fig. VI.) Add two ciphers to the right of the product of twenty-one multiplied by thirty-two, thus obtaining sixty-seven thousand two hundred. To sixty-seven thousand 5 two hundred add one thousand three hundred and forty-four—the product of forty-two multiplied by thirty-two. The sum of these two partial products is sixty-eight thousand five hundred and forty-four, the total product of 10 two thousand one hundred and forty-two multiplied by thirty-two.

If instead of two thousand one hundred and forty-two multiplied by thirty-two we had one hundred and eighty-two thousand one hundred 20 and forty-two multiplied by thirty-two the products of eighteen multiplied by thirty-two and forty-two multiplied by thirty-two would all still appear at the same time, and an operator fairly proficient in mental arithmetic 25 could do the necessary carrying and adding without writing down any numbers.

A device for doing this kind of work would have to contain the products of all whole numbers up to one hundred multiplied by one hundred; but a calculator of such capacity, if constructed according to the principles of this invention, could still be made small enough to carry in the pocket.

When the device is used in an edgewise position, it may sometimes be desirable to entirely omit the retracting mechanism, since each plate rests upon the frame and there is practically no friction of one plate upon another.

40 If most of the sales being made are at the same price per unit of weight or measure, it may be desirable to leave a plate in a reading position, so as not to have to operate it every time a sale is made. Thus, if the retracting-cords were removed and the plate ^{g³} in Fig. VI were not manually adjusted, the device would continue to indicate the total money value of a commodity selling at thirty-two cents per unit of weight or measure. The 45 plate could be returned by the operating instrument when desired.

What I claim as new, and desire to secure by Letters Patent of the United States, is—

1. In a device of the class described, a series 55 of slidable plates each provided with an arm or projection containing a row of apertures, said arms overlapping each other at their edges; substantially as described.

2. In a tabular reference device, a frame, a 60 plurality of longitudinally-slidable plates, an elastic cord and an inelastic clip secured to the ends of the cord and extending across the forward ends of said plates in position to be engaged thereby and to return said plates to 65 their normal position.

3. In a tabular reference device, the combination of a frame; sliding plates; retracting-cords for said plates; and combined means for strengthening the frame and attaching and detaching the cords. 70

4. In a device of the class described, a slotted case, one of the slots being wider than the others, and one of its walls forming a stop, slotted indicating-plates movably mounted in the case, each plate being provided with an 75 arm which extends across said wider slot, said arm being provided with a series of perforations, and movable so as to move each perforation into a position adjacent to said wall.

5. In a device of the class described, a slotted case, one of the slots being wider than the others and one of its walls forming a stop, the distance between the adjacent narrower slots being substantially equal to the width of the wider slot, slotted plates in the case, the 85 slots in the plates corresponding with those in the case, and each plate being provided with a plurality of indicators for each slot and with a shouldered arm which extends across the wider slot, said shoulders being movable into 90 a position adjacent to said wall and its corresponding indicator into register with its respective slot in the case.

6. In a device of the class described, a slotted case, one of the slots being wider than the others and one of its walls forming a stop, the distance between the adjacent slots being substantially equal to the width of the wider slot, and each slot having a column of numbers adjacent thereto, and slotted plates in the 100 case, the slots of which correspond with slots in the case, each plate being provided with a plurality of columns of numbers for each slot, and with a shouldered arm which projects across the wider slot, there being a shoulder 105 for each column of numbers at any slot, said shoulders being each movable into a position adjacent to said stop whereby its respective column of numbers is brought into register with the slots in the case and in the other plates. 110

7. In a device of the class described, a perforated case, stationary supports for the same, the support at one end being notched, clips at said end provided with projections registering with said notches, perforated plates in the 115 case, inelastic clips in position for engaging with said plates, and elastic cords secured to said inelastic clips and extending through said notches and detachably engaging with the projections on the clips at that end of the case. 120

8. In a device of the class described, in combination, a case, a series of plates inclosed in said case and provided with arms containing longitudinal rows of operating-apertures, said rows of apertures being normally exposed on 125 both sides through openings in the case, the plates being superposed in said series and slideable in the same direction.

9. In a device of the class described, a case having sight-openings and a slide within said 130

- case provided with numbers exposable through said sight-openings, said slide being provided with numbered operating-openings, and the case being provided with oppositely-disposed 5 operating-apertures exposing all of the numbered operating-openings on the slide in the normal position of the latter, the ends of said operating-apertures being adapted to act as stops for operating means inserted through 10 said operating-openings.
10. In a device of the class described, in combination, a series of superposed movable members, means for singly extending intermediate members of the series, and two retracting devices for the series, one device engaging with alternate members and the other device with the intermediate members.
11. In a device of the class described, in combination, a series of superposed movable slides, 20 means for singly extending intermediate members of the series, and two elastic cords adapted to retract the entire series, one cord engaging with alternate slides and the other cord engaging with the other slides.
12. In a device of the class described, in combination, a series of superposed longitudinally-slidable plates placed in contact with each other, a suitable casing having one or more sight-apertures, and an elastic retractor engaging forward edges of a plurality of the plates, and thereby holding against frictional displacement the plate or plates contacting 30 with the one being operated.
13. In a device of the class described, in combination, a series of superposed longitudinally-slidable plates having contacting faces, a suitable casing containing one or more sight-apertures, and two retracting devices each engaging forward edges of a plurality of the plates, 40 and thereby holding against frictional displacement the plate or plates in contact with the one being operated.
14. In a device of the class described, in combination, a frame, a series of superposed slides, 45 and two automatic retracting devices, each yieldingly holding alternate slides of said series and leaving free the slides held by the other.
15. In a device of the class described, in combination, a frame, a series of superposed slides, and two elastic cords each yieldingly holding alternate slides of said series and leaving free the slides held by the other.
16. In a device of the class described, in combination, a frame, a series of superposed slides, two automatic retracting devices one of which normally engages shoulders of alternate slides of the series and the other normally engages shoulders of the intervening slides, said slides 60 having cut-away portions preventing more than one retracting device from being operated at a time.
17. In a device of the class described, in combination, a perforated case, plates slidably

mounted therein, elastic cords exterior to the 65 case for engaging with the plates and automatically returning them to the normal position, and supports on the sides of the case adapted to prevent said case from resting upon the cords when it is laid on a plain surface. 70

18. In a device of the class described, in combination, a perforated case, plates slidably mounted therein, elastic cords exterior to the case for engaging with the plates and automatically returning them to the normal position, and means adapted to prevent said case from resting upon the cords when it is laid 75 on a plain surface.

19. In a tabular reference device, in combination, a cover having transverse sight-apertures, a correspondingly-apertured slide having a row of seats, and a stop in line with said seats, the distance between the stop and the seat normally farthest therefrom substantially equaling the distance between two adjacent slots of the slide. 80

20. In a tabular reference device, a series of cards held in pack form, a perforated case inclosing said cards, definite characters upon 90 the cards, definite characters upon the case, means whereby a card may be moved and a character thereon brought into definite relation with a character on the case, and two devices, each yieldingly holding alternate 95 cards and leaving free the cards held by the other.

21. In a tabular reference device, in combination, a frame, a plurality of transverse columns of numbers inscribed thereon; a plurality of superposed plates movably mounted within said frame, said plates having a plurality of transverse slots corresponding respectively to the columns of numbers on the frame, each plate being provided with a succession 100 of seats arranged in a longitudinal row; and a stop in line with the seats in said row, the distance between the seat normally farthest from the stop and the stop being substantially equal to the distance between two adjacent slots of the plate. 105

22. In a tabular reference device, a perforated case, a series of cards held therein in pack form, characters on the cards, and characters on the case, one of said cards having a 110 plurality of means whereby the card may be moved a distance relatively to the position of said means, and two devices, each yieldingly holding alternate cards and leaving free the cards held by the other. 115

23. In a tabular reference device, a perforated case, a series of cards held therein in pack form, characters on the cards, and characters on the case, one of said cards having a 120 plurality of seats whereby the cards may be moved variant predeterminate distances, said distances corresponding to the position of the seats, relatively to one of the walls of one of 125

the perforations in the case, and two devices, each yieldingly holding alternate cards and leaving free the cards held by the other.

24. In a tabular reference device, a series 5 of cards held in pack form, a perforated case inclosing said cards, a table of numbers representing the unknown quantities of mathematical problems inscribed upon the cards, numbers representing the known quantities, 10 means for moving a card to expose to view the number representing the unknown quantity of a problem in definite relation with a number representing one of its known quantities, and two devices, each yieldingly holding alternate cards and leaving free the cards held by the other.

25. In a tabular reference device, a perforated case, a series of contacting cards movably mounted therein, each card having a 20 body portion occupying substantially the entire inner width of the case, definite characters upon the cards, definite characters upon the case, means whereby a card may be moved and a character thereon exposed to view in 25 definite relation with a character on the case, and two devices, each yieldingly holding alternate cards and leaving free the cards held by the other.

26. A tabular reference device comprising 30 a frame; a plurality of superposed slidable plates which are respectively provided with numbers arranged in groups of columns which columns are similarly spaced apart in their respective groups, the groups of columns on 35 a plate being separated by slots; a slotted cover; and means for sliding each plate predetermined variant distances to expose to view any given column through the slot in the cover corresponding to the group of columns 40 to which said given column belongs.

27. In a tabular reference device, in combination, a frame; a plurality of transverse columns of designating-numbers inscribed thereon; a plurality of superposed plates movably 45 mounted within said frame each of said plates being provided with a longitudinal row of seats, there being indicating-numbers for said seats, said plates each also having a plurality of transverse slots corresponding respectively 50 to the aforementioned columns of designating-numbers on the frame; a table of numbers on the plates, each space between two adjacent slots of a plate bearing thereon a division of the table arranged with the numbers 55 in longitudinal rows and transverse columns, each of the longitudinal rows being in line with its designating-numbers on the frame, and the columns of each aforementioned division of the table corresponding respectively 60 to the aforementioned seats of the plate.

28. In a tabular reference device, in combination, a cover provided with a plurality of transverse slots; a column of designating-numbers along a side of each of said slots; a plu-

rality of superposed plates movably mounted 65 beneath the cover, each of said plates being provided with a longitudinal row of seats, there being indicating-numbers for said seats, said plates having transverse slots normally coinciding with the slots in the cover; a table 70 of numbers inscribed on the plates, each portion of a plate between two adjacent slots bearing thereon a division of the table having the numbers thereof arranged in longitudinal rows and transverse columns, the columns of 75 each said division of the table corresponding respectively with the aforementioned seats of the plate, so that, throughout its several divisions of the table columns corresponding to each other are provided with a common seat. 80

29. In a tabular reference device, in combination, a frame; and a series of superposed perforated plates, each plate of the series having a portion cut away from the lateral edge adjacent to one side of the frame, the intervening plates each being cut away from the other lateral edge, for the purpose specified. 85

30. A tabular reference device comprising a frame; a plurality of transverse columns of 90 designating-numbers inscribed thereon; a longitudinally - movable plate mounted in the frame; a table of numbers arranged in longitudinal rows and in groups of transverse columns, each of the longitudinal rows alining with its proper designating number on the 95 frame, said plate being also provided with a succession of seats equal in number to the columns of any given group so that columns corresponding to each other throughout the several groups may have a common seat; and a 100 stop for said seats.

31. A tabular reference device comprising a frame; a plurality of transverse columns of 105 designating-numbers inscribed thereon; a longitudinally - movable plate mounted within the frame; a table of numbers on the plate arranged in longitudinal rows and in equal groups of transverse columns, each of the longitudinal rows alining with its proper designating-number on the frame, said plate being 110 also provided with a succession of perforations adapted to receive a removable instrument from either side thereof, said perforations being equal in number to the columns of any given group so that columns corresponding to each other throughout the several groups may have a common seat; and a stop 115 for said seats.

32. In a device of the class described, in combination, a frame; a series of superposed slides; means for moving said slides from the normal position; and two elastic cords respectively attached to the rear portion of opposite sides of the frame and extending over forward ends of the slides, one of said cords normally 120 impinging upon forward ends of alternate slides of the series and the other cord likewise 125 impinging upon the intervening slides, said

slides having cut-away portions preventing more than one cord being extended at a time by the operation of a plate.

33. In a device of the class described, in combination, a cover, a column of designating-numbers thereon, a longitudinally-slidable plate within said cover, a group of numbers arranged in longitudinal rows and spaced columns on said plate, each row in line with a number of the column on the cover, there being a numbered operating-seat corresponding to each column on the plate, and a stop for the seats whereby the column corresponding to any seat may be displayed adjacent to said column on the cover.

34. In a device of the class described, in combination, a frame, a longitudinally-movable plate within said frame, a cover for said plate, a transverse column of designating-numbers along an edge of the cover, a group of numbers arranged in longitudinal rows and spaced columns on the plate, each row corresponding to a number of the column on the cover, there being a numbered operating-seat corresponding to each column in the group of numbers on the plate, and a stop for the seats whereby the column corresponding to any seat may be displayed adjacent to said edge of the cover.

35. In a device of the class described, a series of superposed longitudinally-slidable plates, a suitable casing having a sight-opening, and an elastic retractor engaging forward edges of a plurality of the plates.

36. A device of the class described, a case having sight-openings, and a slide within said case provided with numbers exposable through said sight-openings, said slide being provided with numbered operating-openings, and said case being provided on one side with an operating-aperture exposing all of the operating-openings in the slide in the normal position of the latter, the ends of said operating-aperture being adapted to act as stops for operating means inserted through said operating-openings, and said case being cut away on the other side opposite said operating-apertures to permit free penetration of operating means through said operating-openings.

In testimony whereof I have signed my name to this specification, in the presence of two subscribing witnesses, at Los Angeles, California, this 12th day of February, 1902.

ALBERT H. MERRILL.
